UNITED STATES PATENT OFFICE.

GUSTAVUS A. DUNCAN, OF DEADWOOD, SOUTH DAKOTA.

PROCESS OF TREATING SLIMES IN ORE REDUCTION.

SPECIFICATION forming part of Letters Patent No. 787,878, dated April 18, 1905.

Original application filed March 27, 1904, Serial No. 205,070. Divided and this application filed July 2, 1904. Serial No. 215,173.

To all whom it may concern:

Be it known that I, GUSTAVUS A. DUNCAN, a citizen of the United States, residing at Deadwood, in the county of Lawrence and 5 State of South Dakota, have invented new and useful Improvements in Processes of Treating Slimes in Ore Reduction, of which the following is a specification, reference being had to the accompanying drawings, forming a part thereof.

This application is a division of my application, Serial No. 205,070, filed March 27, 1904.

This invention relates to the treatment of slimes containing metal values, its purpose 15 being to provide a simplified and economical process for separating the metal values from such slimes.

It consists of the steps and operations of the process hereinafter set out, and specified 20 in the claims.

In the drawings I have shown apparatus suitable for employment of the herein-described process which constitutes the present invention. This apparatus, however, is illustrated only for the purpose of rendering the process intelligible, and it is in many of its essential features the subject of other applications for patent—such as, for example, the application of Oliver P. Ankeny, Serial No. 30 198,076, filed March 14, 1904.

In the drawings, Figure 1 is a plan view of an apparatus employed in the herein-described process constituting my invention. Fig. 2 is a vertical section through one of the tanks, section being made at the line 2 2 on Fig. 1.

In practicing my invention I employ one or more tanks or vats A, in each of which there is suspended a filtering-cell B, which is only enough less in horizontal dimensions 40 than the tank in which it is suspended to leave room for the accumulation upon its lateral surfaces of a predetermined thickness of slimes and enough additional space outside the same when so accumulated for the necessary circulation of the liquor or cleansing-water at the different stages of the process hereinafter described. In each of the cells there are any desired number of pipes C C C, 45 connected to a pumping apparatus, conveniently represented at D, for sucking the

liquid in the tank and in which the cells are immersed through the filtering-walls of the cells to cause the deposit of solids upon the outer walls of the latter. These pipes for this purpose extend from the top down to a 55 point near the bottom of the cells, where they open to take in the liquid. The liquid shown in the tank in Fig. 2 may be understood to be slime-bearing liquid, the slime being supposedly charged with metal values which it is the 60 purpose of the process to extract and the liquid being also charged with a proper metal-solvent liquor adapted to the mineral character of the slimes. Pipes E E E, extending longitudinally under the bottom of each tank, 65 have their outer curved surface only partly exposed and are perforated at the lower sides for the discharge of air at a multiplicity of points into the liquid in the tanks to keep the same agitated and cause the slimes to remain 70 in suspension. These pipes may be understood to be connected with any source of air, (not shown,) by which the air-discharge is maintained as described. The slime-bearing liquid is supplied continuously at the top 75 of the tank, as indicated by the pipes F, extending along the top of the tanks, and discharging into them at frequent intervals, (indicated by the discharge-nipples F' F',) the supply being made adequate to make good 80 the drainage effected by suction through the filtering-walls of the cells and carried off by the pipes C until the desired thickness of deposit of slime is produced upon the outer walls of the cells. Thereupon the supply of slime- 85 bearing liquid being cut off the suction will be continued through the pipes C until the liquid is substantially exhausted from the tank down to the bottom of the cell, the air-supply through the pipes E being reduced, if 90 necessary, as the level of the liquid falls, so as not to produce undue agitation in the reduced quantity. A fresh metal-solvent liquor adapted to attack and take up the metal values still contained in the slimes will now be introduced 95 into the tank, either through the pipes E or if by reason of the smallness of their discharge-apertures this method is too slow then through similar pipes G, having freer discharge at frequent intervals, (indicated by 100

the apertures *g*, for example,) and the tank being kept filled with such solvent liquor, suction being applied as before through the pipes *C*, such solvent liquor will be sucked in 5 through the slimes deposited on the cells and will dissolve out the metal values in the latter, and the discharge from the pumps being collected may be treated in the customary manner for recovery of metal values from 10 the liquor thus drawn through the slimes. After this step in the operation has been continued for a sufficient length of time to extract the metal from the slimes to such degree as may be economically effected in this 15 manner the metal-solvent liquor will be withdrawn by cutting off the supply and continuing the suction until the tank is empty or by directly draining the tank through the bottom, if preferred, and a supply of clear water 20 will be furnished through the pipes *E* or *G*. The tank being filled with water to the top of the cells and the section continued, the remainder of metal-solvent liquor with whatever metal values it may carry will be washed 25 out of the slimes and collected for further treatment. After the slimes have been thus thoroughly washed out, so that not only all the metal values possible but all the solvent liquor worth recovering have been washed 30 out, the slimes may be detached from the outer surface of the cells by any convenient means. A satisfactory means consists in reversing the pressure, so that water is forced into instead of drawn out of the cells and by 35 the pressure from within operating outward through the canvas forces the accumulated load of slimes off from the latter, so that, being detached, it falls bodily into the tank and can be carried away through the discharge-passages upon opening the same and flushing 40 out the tank with clear water. This process also tends to clear the interstices of the canvas, leaving it in proper condition for repetition of the filtering action, when suction is 45 again applied as at first. It is desirable also to flush off the outer surface of the canvas and assist the action of the interior pressure in detaching the slimes, and this is accomplished by means of water-jets directed 50 against the outer surface of the cells at the top of the slime deposit, which is thus attacked in position to leave no marginal residuum adhering to the canvas. For this 55 step of the process I provide a horizontal pipe *J*, extending along each side of each cell at the top with discharge-apertures or nozzles for directing a multiplicity of jets of water inward and downward against the sides of the cells. A valve *K* controls this entire 60 system of flushing-pipes. With slimes of certain character the exterior flushing alone may be adequate for detaching the residuum and washing the outer surface, and in other instances the character of the slimes may be 65 such that the interior pressure alone will de-

tach them cleanly; but in most cases it is desirable to employ the two expedients coöperatively, as described. In the drawings there is shown means for producing the suction and pressure only in conventional manner without regard to structural details. Any familiar means for producing these effects may be employed. In the drawings it may be understood that the pump *D* operates to withdraw the liquid from and through 75 the cells, as described, and that the pipe *M* is connected with a source of water under pressure for operating in the opposite direction when the valve *M'* is opened and the pump is not in operation. The water supplied 80 through the pipe *M* for detaching the slimes, as above described, serves also to assist in flushing out the tank and delivering the residual mud therefrom.

With certain sorts of slimes the deposit 85 formed upon the cell by exhaustion of the liquid as described from within may have a tendency to crack or may be without cracking quite porous, so that when the supply of slimes is cut off, the exhaustion continuing 90 and lowering the level of the liquid in the tank, the air will enter so easily through the deposit as to partially defeat the action of the suction in exhausting the tank to the bottom, and some slimes may be of such quality 95 that they will not be retained after the liquid is withdrawn from the exterior, but will fall off in cakes. In such cases when the supply of slimes is cut off a corresponding supply of solvent liquor will be admitted at 100 the bottom through the pipes provided for that purpose, and thus the liquid will be maintained in the tank at the full level, becoming gradually deprived of the solid matter by deposit, so that it will eventually consist only of the solvent liquor, as would be the case if the slime-bearing liquor had been first exhausted and the other liquor substituted. In like manner after drawing the 105 solvent liquor through the slimes for a sufficient time to complete the process of dissolving out the metal values the liquid-supply will be changed to clear water while the tank is still full, and the suction being continued the liquid will gradually change from 110 solvent to pure water, and then being continued long enough to complete the washing, the supply being wholly cut off, the suction will be continued until the tank is exhausted, and if the deposit tends to break away and 115 fall in this process no damage will be done, because this will be only in anticipation of the next step, which will consist in freeing it by the means described.

I claim—

1. The process of treating ore slimes which consists in accumulating the slimes upon the exterior of a filtering-cell immersed in the slime-bearing liquid, by suction from within the cell and exhausting the liquor from about 120

such accumulated slimes, surrounding the cell having the slimes thus accumulated thereon with fresh metal-solvent liquor, and drawing such liquor by suction within the 5 cell through the slimes so accumulated on its exterior, and subsequently detaching the residual slimes from the cell.

2. The process of treating ore slimes which consists in accumulating the slimes on the 10 exterior of a filtering-cell by suction from the interior of the cell while the latter is immersed in the slime-bearing liquid contained in a tank into which the cell intrudes; cutting off the supply of slime-bearing liquid 15 from about the cell and substituting a metal-solvent liquor; drawing such liquor into the cell through the slimes accumulated thereon, and conducting it away; withdrawing the solvent liquor from around the cell, and subsequently 20 detaching the residual slimes from the cell.

3. The process of treating ore slimes which consists in accumulating the slimes on the exterior of a filtering-cell by suction from 25 within the cell while the latter is immersed in the slime-bearing liquid; cutting off the supply of slime-bearing liquid from around the cell; substituting a metal-solvent liquor; sucking such liquor through the slimes so 30 accumulated into and through the cell; cutting off the supply of solvent liquor from around the cell; substituting a non-solvent liquid; sucking such liquid through the residual accumulated slimes for washing the solvent 35 liquor from the latter, and subsequently detaching the residual slimes from the cell.

4. The process of treating ore slimes which consists in accumulating the slimes on the exterior of a filtering-cell by suction from 40 within the cell while the latter is immersed in the slime-bearing liquid; sucking the metal-solvent liquor through the slimes so accumulated thereon; subsequently directing water-jets against the accumulated 45 slimes for detaching them from the cell and cleansing the latter.

5. The process of treating ore slimes which consists in accumulating the slimes on the exterior of a filtering-cell fixedly intruded 50 into a tank; surrounding the cells within the tank with a slime-bearing liquid, and applying suction within the cells for drawing the liquid through the cell-walls; cutting off the

supply of liquid from around the cells and substituting a metal-solvent liquor; sucking 55 such metal-solvent liquor through the accumulated slimes into and through the cell; cutting off the supply of solvent liquor from the tank; substituting non-solvent liquid; sucking such non-solvent liquid through the 60 accumulated slimes into and through the cell; withdrawing the non-solvent liquid and detaching the residual slimes from the cell.

6. A process of treating ore slimes which consists in accumulating the slimes on the 65 exterior of a filtering-cell by suction from within the cell while the latter is immersed in the slime-bearing liquid; drawing the metal-solvent liquor by suction into the cell through the slimes so accumulated thereon 70 and conducting away the metal-bearing liquor; cutting off the supply of solvent liquor from around the cell and substituting a non-solvent liquid; sucking such liquid through the residual accumulated slimes for washing 75 the solvent liquor from the latter, and subsequently forcing water into and out through the walls of the cell to detach the residual slimes from the exterior thereof.

7. A process of treating ore slimes which 80 consists in accumulating the slimes on the exterior of a filtering-cell by suction from within the cell while the latter is immersed in the slime-bearing liquid; cutting off the supply of slime-bearing liquid from around 85 the cell; substituting a metal-solvent liquor; sucking such liquor through the slimes so accumulated into and through the cell; cutting off the supply of solvent liquor from around the cell; substituting a non-solvent liquid; 90 sucking such liquid through the residual accumulated slimes for washing the solvent liquor from the latter; applying liquid-pressure within the cell operating outward for detaching the residual slimes, and simultaneously directing water-jets against the outer surface of the cell at the top of the accumulated slimes.

In testimony whereof I have hereunto set my hand, in the presence of two witnesses, 100 at Deadwood, South Dakota, this 23d day of June, A. D. 1904.

GUSTAVUS A. DUNCAN.
